UNITED STATES PATENT OFFICE.

AUGUST SCHLICHT, OF CANTON, KANSAS.

MOLD.

1,074,471.

Specification of Letters Patent.

Patented Sept. 30, 1913.

Application filed July 27, 1912. Serial No. 711,939.

To all whom it may concern:

Be it known that I, AUGUST SCHLICHT, a citizen of the United States, residing at Canton, in the county of McPherson and State 5 of Kansas, have invented certain new and useful Improvements in Molds; and I do hereby declare the following to be a full, clear, and exact description of the invention, such as will enable others skilled in the art 10 to which it appertains to make and use the same.

My invention relates to molds, and more particularly to that class of molds for forming culverts.

15 The object of my invention is to provide a sectional mold comprising a plurality of adjustable parts, whereby culverts of different sizes may be formed with one and the same mold.

20 Another object is to provide a mold of this character with wing boxes for forming the end walls or wings for the culvert integral with the main portion thereof.

25 Other objects and advantages will be hereinafter set forth and pointed out in the specification and claim.

In the accompanying drawings which form a part of this application, Figure 1 is a perspective view of a mold for a culvert 30 constructed in accordance with my invention. Fig. 2 is an end view thereof showing the wing box removed. Fig. 3 is a fragmentary sectional view on the line 3—3 of Fig. 1, and, Fig. 4 is a fragmentary elevation of the inner face of the side walls of the mold showing a locking means for retaining the sections thereof in alinement.

Referring more particularly to the drawings, in which similar reference characters 40 denote corresponding parts throughout the several views, 1 indicates the side walls of the structure, which walls are preferably formed in sections, as shown in Fig. 2, two of the sections of each wall having their 45 abutting surfaces beveled, as shown, at 2, to provide a key block 3 by means of which the walls may be readily taken down after a culvert has been formed thereover. The ends 50 of the sections are provided with alined slots 4, within which are positioned bolts or rods 5 for retaining the sections in perfect alinement. In some instances, however, where culverts of great length are built it is neces-

sary to provide means for retaining the sections in alinement adjacent the center thereof, in which instance, I provide each of the sections with a bracket arm 6^a, except the key block 3 and the bottom section 2 and to the latter is pivoted the locking arm 8^b adapted, when the sections are set up, to be 60 engaged beneath each of the bracket arms 6^a. The walls are properly held in spaced relation by means of braces 2^a, comprising parallel end pieces secured upon the upper surface of the upper section of each wall, 65 and extending longitudinally thereof, is an angle iron 6. Positioned between the side walls and having their longitudinal edges disposed within the angle iron 6 are the overlapped top sections 7. For forming the 70 end walls or wings of the culvert, I provide wing boxes 8^a, comprising side walls 9 secured at the ends of the walls 1 by means of pivoted locking arms 10 having nuts 11 upon their outer ends, and secured to the top sec- 75 tions by means of threaded lugs 10^a and nuts 11^a. The ends 12 and sides 15 of the wing boxes are formed integral and are attached to the side walls 9 by the threaded lugs and nuts. As clearly shown, the central portion 80 of the wall 9 between the walls 1 and the top sections 7 of the culvert mold is cut away as shown at 9^a, whereby the water may flow thereunder while a culvert is being constructed. The side wall 15 is provided with 85 an aperture 12^a, conforming in shape to the shape of the walls 1 and top sections 7 but is of greater size than the latter.

By the construction of mold as herein disclosed, it will be obvious that when the cement is poured upon the body thereof and the wing boxes filled, the body portion of the culvert and the wings or end walls thereof will be formed integral, the resulting structure being extremely rigid. 90

To take down the mold the first step is to remove the wing boxes by loosening the nuts 11 and 11^a, when the bolts 5 may be readily removed. After the braces 2^a have been removed, the walls and apertured top sections 100 7 may be quickly disassembled by merely loosening the key block 3.

What I claim is:—

The combination with a culvert mold having sectional side walls and a top, the ends 105 of the sections of the side walls being slotted

vertically, a rod positioned in the slots of each wall; of a two-part wing mold having a side adapted to be secured against the ends of the walls to retain the rods in position and 5 another side formed integral with the ends, and means to detachably secure the parts together.

In testimony whereof I have signed my name to this specification in the presence of two subscribing witnesses.

AUGUST SCHLICHT.
